UNITED STATES PATENT OFFICE.

HOWARD J. TREGANZA, OF BROOKLYN, NEW YORK, ASSIGNOR TO ANSONIA CLOCK COMPANY, OF BROOKLYN, NEW YORK, A CORPORATION OF CONNECTICUT.

CLOCK.

Application filed February 21, 1924. Serial No. 694,248.

To all whom it may concern:

Be it known that I, HOWARD J. TREGANZA, a citizen of the United States, and a resident of Brooklyn, in the borough of Brooklyn, county of Kings, city and State of New York, have invented a certain new and useful Clock, of which the following is a specification.

The invention relates to clocks of the balance wheel type, and particularly to the regulating mechanism thereof, and has for its objects to produce a time piece in which the regulating scale and pointer or index are more conveniently located than in clocks at present in use, whereby regulating may be accomplished with less effort and with less eye-strain.

A further object is to provide means whereby regulation may be effected with greater accuracy.

A further object is to remove the manually operated part of the regulating mechanism from the scale.

A further object is to construct the manually operated portion of the regulating mechanism of such strong and rugged character that it will not be easily bent or broken.

A still further object is to provide means whereby the scale will not be obliterated or obscured.

A still further object is to provide means whereby the movement of the pointer or index will be relatively to that of the manually operated element of the regulating mechanism.

These and further objects will more fully appear in the following specification and accompanying drawings considered together or separately.

One embodiment of the invention is illustrated in the accompanying drawings, in which like parts in all of the several figures are designated by corresponding characters of reference, and in which—

Fig. 1 is a front elevation of a portion of a clock movement showing a frame, the balance wheel, the hair spring and the regulating mechanism.

Fig. 2 is a horizontal sectional view of a portion of a clock casing taken on a line indicated by 2—2 of Fig. 3.

Fig. 3 is a front elevation of the dial illustrating the scale and the pointer or index.

Fig. 4 is a detail end elevation of a portion of the regulating mechanism, and

Fig. 5 is a detail view of a modification.

In the drawings 1 designates the front movement frame member, and 2 the rear frame member. The members are spaced apart and secured to the back plate 3 of a clock casing by means of pillars 4, and the movement proper 5 is positioned between the members, as is common.

Loosely pivoted in the upper part of the frame is the balance wheel arbor 6 carrying the usual balance wheel 7, and to which one end of the hair-spring 8 is secured. The opposite end of the spring is secured to a keeper 9 forming part of the frame 1. The balance wheel is oscillated in the usual manner by means of a lever 10 operated by the usual pallet and pallet wheel.

Rotatably mounted on the frame 1, and in axial alinement with the arbor 6 is a sector 11 carrying the usual stirrup 12 through which the outer convolution of the spring 8 passes, and by means of which the effective length of the spring is adjusted. The sector 11 also carries projecting therefrom an arm 13 which projects through a segmental slot 14 in the bottom of the dial pan 15, and through a similar slot in the dial card 16. On the end of the arm 13 is a pointer or index 17, and below the slot in the dial card is a scale 18 with which the index cooperates. The index is usually at right angles to the arm 13, and to permit of its passage through the slot 14 in order to be visible from the front, a notch 19 is formed in one side of the slot, as shown.

One edge of the sector 11 carries a curved rack 20 which is engaged by a toothed element 21 carried at one end of a shaft 22 journaled in, and extending through the frames 1 and 2. That end of the shaft opposite the element 21 extends through the back plate 4 and is provided with an oper-

ating member, as for example, a wing head 23.

It will be understood that the clock setting knob 24 together with other manually operated elements of the clock, such as the winding knob or knobs, and alarm setting and cut out elements, if used, also are on the back plate 4.

In the embodiment of the invention illustrated in Figs. 1, 2 and 4, the lever 11 is geared down relatively to the shaft 22 whereby the rotary movement of the head 23 will be greater than that of the lever.

In the modification illustrated in Fig. 5 the movement of the member 11^a, which is illustrated as in the form of a pinion, is accelerated relatively to that of the element 21^a, whereby the stirrup 12^a and index 17^a may be moved by the engagement of the teeth 20^a and 22^a, and the slot through which the pointer projects may be made longer whereby closer regulation may be accomplished.

It is to be understood the rack 20 and element 21 may be of any other suitable radial lengths if desired.

By placing the scale on the dial of the clock the same will be as easily visible as the hour, minute and second markings, and of the alarm setting markings, when used. The markings of the scales being behind the glass 24 will be protected from dust and dirt, and the glass will prevent the entrance of dust or dirt through the slot.

The manually operated part, the head 23, of the regulating is situated on the back of the clock casing, as are all of the other manually operated parts of the clock, where it is natural to look for such elements, and the indicator is on the dial where it is natural to look for all of the elements which may be operated from the back.

The arm 13 and index 17 may be as light or lighter than those at present in use, and as they are not handled by the operator, there will be no danger of breaking them. The sector 11, the element 21, the shaft 22 and the head 23 may be made as strong and rigid as required to permit of rough handling.

In accordance with the provisions of the patent statutes the principle of the invention has been described, together with the apparatus which is now considered to represent the best embodiment thereof, but it is desired to have it understood that the apparatus shown is merely illustrative, and that the invention may be carried out in other ways.

The invention having been described what is claimed as new and desired to be secured by Letters Patent, is

1. In a clock, regulating mechanism comprising indicating means and operating means therefor, said means being spaced

apart, the indicating means being located at 65 and visible from the front of the clock.

2. In a clock, regulating mechanism comprising indicating means and operating means therefor, said means being spaced apart, the indicating means being located 70 at and visible from the front of the clock, the operating means being located at the back of the clock.

3. In a clock, regulating mechanism comprising indicating means and operating 75 means therefor, said means being spaced apart, the indicating means being located at and visible from the front of the clock, the operating means being located at the back of the clock and outside of the clock casing. 80

4. In a clock having a casing and a dial visible through the casing, regulating mechanism comprising indicating means and operating means, said indicating means extending through the dial, and said operating means extending through that portion of the casing opposite the dial. 85

5. A clock having a frame, a movement carried by the frame, a dial carried by the frame, said movement comprising a balance wheel and a balance spring, a lever pivoted to the frame at one side of the movement, said lever engaging the spring, a pointer carried by the lever, said pointer passing through the dial, a shaft, connections between the shaft and lever for moving the latter, and means carried by the shaft for rotating the same, said rotating means being on the opposite side of the movement from the lever. 90

6. A clock having a frame, a movement carried in the frame, a dial carried by the frame, there being a segmental slot in the dial, graduations on the dial in proximity to the slot, said movement comprising a balance wheel and a balance spring, a lever pivoted to the frame, a stirrup carried by the lever and through which the spring passes, an arm carried by the lever, said arm extending through the slot, a range of gear-teeth on the lever, a shaft journaled in the frame, a range of gear-teeth on the shaft, said ranges being in mesh, and means for rotating the shaft, said means being located on the opposite side of the movement 105 from the lever. 110

7. A clock having a frame, a movement carried in the frame, a dial carried by the frame, there being a segmental slot in the dial, graduations on the dial in proximity 120 to the slot, said movement comprising a balance wheel and a balance spring, a lever pivoted to the frame, a stirrup carried by the lever and through which the spring passes, an arm carried by the lever, said arm

extending through the slot, a range of gear-teeth on the lever, a shaft journaled in the frame, a range of gear-teeth on the shaft, said ranges being in mesh, and means for 125

rotating the shaft, said means being located on the opposite side of the movement from the lever, a pointer carried on the extremity of the arm and cooperating with the graduations, there being a notch in the slot whereby the pointer may be passed through the slot from the rear of the dial.

This specification signed and witnessed this 15th day of February, 1924.

HOWARD J. TREGANZA.
